UNITED STATES PATENT OFFICE.

JOSEPH W. CALEF, OF NORTH EASTON, ASSIGNOR OF ONE-HALF TO GEORGE B. PARKINSON, OF BOSTON, MASSACHUSETTS.

SHEARS.

SPECIFICATION forming part of Letters Patent No. 240,884, dated May 3, 1881.

Application filed March 5, 1881. (Model.)

To all whom it may concern:

Be it known that I, JOSEPH W. CALEF, of North Easton, in the county of Bristol and State of Massachusetts, have invented certain new and useful Improvements in Shears; and I do hereby declare that the following is a full, clear, and exact description of the invention, which will enable others skilled in the art to which it appertains to make and use the same, reference being had to the accompanying drawings, which form a part of this specification, and in which—

Figure 1 is an end or edge view. Fig. 2 is a sectional view; and Fig. 3 is a perspective view of the sliding cutter jaw or blade with its link, showing also the upper part of the lever or handle with which it is connected.

Similar letters of reference indicate corresponding parts in all the figures.

My invention has relation to hand-shears for cutting sheet metal or other tough material; and it consists in the improved construction and combination of parts as hereinafter more fully described, whereby the shears are adapted to cut through the sheet metal or other material operated upon with comparatively little expenditure of power.

In the annexed drawings, A and B represent the jaws or cutters of my improved shears, the base A' of one of which has a chamber, a, open at both ends and at the top and bottom, and recessed or grooved longitudinally, as shown at b, to form ways for the shank or base B' of the sliding jaw B, which is inserted into and works in the chamber a.

At the inner end of the base B'—that is, the end opposite to its jaw B—is pivoted, in a downward-projecting stud, d, a link or arm, C, which extends back under the base, and is pivoted at its other end in the upper corner of the lever or handle D, which is cut out or recessed, as

shown at f, to receive it. That part of lever D D' which extends into the chambered base A' is flattened and made with a shoulder or projection, g, opposite to its recessed part f, through which the fulcrum pin or bolt E is inserted. The jaw A and its chambered base A' are in one piece with the handle F.

By the construction and combination of the jaw B with its shank or base B', rearwardly-extending link C, and lever D D', all these parts, when properly connected, may be inserted and fulcrumed into the chambered base A' of the opposite jaw, the handle D working on the same side as the jaw B, which it operates, so that all that remains to complete the tool is to insert the fulcrum pin or bolt E.

From the foregoing description, taken in connection with the drawings, the operation of my improved shears will readily be understood, and requires no further explanation.

I claim and desire to secure by Letters Patent of the United States—

As an improvement in shears, the cutter jaw B, having the base B', provided at its inner end with the link C, in combination with the flattened lever D D', having recess f and perforated shoulder g, and the jaw A, constructed with the chambered base A', having side grooves or recesses b, and handle F, said lever D D' having its fulcrum upon the pin or bolt E, inserted through its perforated shoulder g, substantially as and for the purpose herein shown and specified.

In testimony that I claim the foregoing as my own I have hereunto affixed my signature in presence of two witnesses.

JOSEPH W. CALEF.

Witnesses:

AUGUST PETERSON,
JAMES H. MANDEVILLE.
